INVENTOR

MAX. M. WEISS.

BY

Wm. F. Gandy
ATTORNEY

UNITED STATES PATENT OFFICE.

MAX M. WEISS, OF BROOKLYN, NEW YORK, ASSIGNOR OF ONE-THIRD TO FRANK J. BOEHM AND ONE-THIRD TO BENJAMIN GLICK, BOTH OF BROOKLYN, NEW YORK.

MOP.

Application filed November 14, 1924. Serial No. 749,811.

To all whom it may concern:

Be it known that I, MAX M. WEISS, a citizen of the United States, residing at Brooklyn, in the county of Kings and State 5 of New York, have invented certain new and useful Improvements in Mops, of which the following is a specification.

This invention relates to washing devices and more particularly is directed to an improved fountain mop which is adapted to be attached to the end of a hose for cleaning automobiles and the like purposes.

Among the objects of the invention is to provide an improved device of the character 15 described which is normally arranged to operate with a continuous supply of water to the brush or mop end thereof for facilitating the cleaning of the surfaces of automobiles or for like purposes, without marring 20 or scratching the polish or finish of such surfaces, which is simple in construction, cheap to manufacture, neat in appearance, and efficient and practical to a high degree.

Other objects of this invention will in 25 part be obvious and in part hereinafter pointed out.

The invention accordingly consists in the features of construction, combinations of elements and arrangement of parts which 30 will be exemplified in the construction hereinafter described, and of which the scope of application will be indicated in the following claims.

In the accompanying drawing, in which 35 is shown one of the various possible illustrative embodiments of this invention,

Fig. 1 is a perspective view of a washing device embodying the invention;

Fig. 2 is a cross-sectional view taken on 40 line 2—2 in Fig. 1;

Fig. 3 is a cross-sectional view taken on line 3—3 in Fig. 1; and

Fig. 4 is a perspective view of a modified form of the invention.

Referring in detail to the drawing, 10 indicates generally a fountain mop washing device embodying the invention and as will be seen from Figs. 1, 2 and 3, comprises a head 11 which may be of any suitable shape, preferably triangular, to present a tapered leading end 11^a to facilitate reaching in corners, and an elongated tubular handle member 12 having the outlet end 12^a thereof secured to the under side of the head 11,

said handle member 12 extending outwardly 55 from the side 11^b, opposite the end 11^a, and at an angle with the top side 11^d of said head. The lead end 11^a and other corners of the head are preferably rounded so as to prevent scratching the surfaces of the object cleaned.

The head 11 may be made of any suitable material, but is preferably formed of sheet metal into a hollow member having the top side 11^d and depending side walls 11^c to enclose a recess 11^f of the mop 13. To provide a releasable fastening means for securely holding the mop or brush 13 in the head 11, the marginal portions of the walls 11^c are bent to form inturned flanges 11^e which are 65 effective to engage with an expansible core 13^a of mop 13 as shown in Fig. 2. To provide a neat finish and make the exterior surfaces of the head wear proof, non-corroding and rustless, the head may preferably 70 be nickel plated or otherwise be suitably treated.

The handle member 12 is preferably made of tubing and may be finished like head 11, the device 10 being best finished in one operation after the head 11 and handle 12 have been assembled. As seen in Figs. 2 and 3, the outlet end 12^a of member 12 passes through side 11^b of the head 11, is 80 preferably flattened, and is secured to the underside of the head 11 by any suitable means such as by soldering. The end 12^a may be shaped and positioned to extend into said head 11 a substantial distance and serves to efficiently distribute the flow of 85 water to all portions of the mop 13. The inlet end 12^b of the handle may be provided with suitable coupling means 14 for connecting the device 10 to a hose (not shown) in the well known manner.

In Fig. 4 is shown a modified form of the invention indicated generally at 15 and comprising a head 11 and a water supply tubular member 16, the latter having an outlet end 16^a which is similar to end 12^a of the handle member 12, and a short extension inlet end 16^b which may be adapted to be attached to a flexible hose 17 in the well known manner. In order to provide 100 convenient means for manipulating the device 15, a strap 17 may be secured to the head 11 in any suitable manner as by detachably fastening the hook end 17^a, said

strap 17 and the head 11 being constructed to permit the insertion of the operator's hand in the well understood manner.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. An article of manufacture of the character described comprising a head having an inturned peripheral flange adapted to

releasably engage with a mop, and a flattened nozzle secured to the under side of the head, said nozzle extending through an opening provided in said flange.

2. An article of manufacture of the character described comprising a triangular shaped head having the marginal portions thereof bent to form a side wall and inturned flanges adapted to releasably engage a similarly shaped mop, and a tubular member having one end thereof secured to the under side of the head and extending outwardly from a mid-portion of one of the flanges of said head, said end extending toward the opposite corner of said head a substantial distance along the under side thereof for distributing a flow of water through said member to all portions of said mop.

In testimony whereof I affix my signature.

MAX M. WEISS
